UNITED STATES PATENT OFFICE.

HERMAN OSSWALD, OF RICHMOND HILL, NEW YORK.

AUTOMATIC THREADING MACHINE.

1,391,492.

Specification of Letters Patent. Patented Sept. 20, 1921.

Application filed November 29, 1919. Serial No. 341,421.

To all whom it may concern:

Be it known that I, HERMAN OSSWALD, citizen of the United States, and resident of Richmond Hill, in the county of Queens and State of New York, have invented certain new and useful Improvements in Automatic Threading-Machines, of which the following is a specification.

This invention relates to improvements in automatic threading machines. The object of the invention is to provide an automatic machine for threading caps such as are used on fruit jars, cold cream jars, oil cans, bottles and the like. One object of the invention is to provide a threading machine of generally improved construction. Another object is to provide a threading machine with an automatic feed so as to increase the output of the machine and eliminate dangers incidental to hand feeding. Other objects will appear as this specification proceeds. Accordingly my invention is embodied in an automatic threading machine arranged, designed and constructed as hereinafter set forth while reference is had to the accompanying drawings in which—

Figure 1 is a side elevation of an automatic threading machine embodying the invention with parts omitted and parts broken away.

Fig. 2 is a partial end view of the machine looking in the direction of arrow 2 in Fig. 1.

Fig. 3 is a view of a modified form of knock out mechanism.

Fig. 4 is a sectional view of the machine taken on the line 4—4 of Fig. 1.

Fig. 5 is a view of the lower end of the automatic feed chute.

Fig. 6 is a sectional view on the line 6—6 of Fig. 5.

Fig. 7 is a plan view of Fig. 5.

Fig. 8 shows one type of a cap adapted to be fed automatically to the machine.

Fig. 9 is a sectional detail view on line 9—9 of Fig. 4.

Fig. 10 is a sectional detail view on line 10—10 of Fig. 4.

Referring to the drawings the several parts of the machine are mounted upon a suitable frame 10 which in turn rests on legs 11, 11. The frame forms three alined bearings 12, 13 and 14 in which the main driving shaft 15 is journaled. Any suitable means, not shown, may be employed to drive the main shaft. The main frame also forms two alined bearings 16 and 17 for the re-

ception of the fixed die shaft 18. Motion is imparted to the die shaft 18 from the main shaft 15 by means of two intermeshing gears 19 and 20. The die shaft carries and drives the fixed die 191 which may be of any type and size required for the threading of the particular cap 21.

The threading of the cap takes place between the two coöperating dies, one of which is preferably stationary and receives the cap to be threaded, while the other die is movable and is adapted to be brought into contact with the fixed die. The cap is then threaded between the dies by rotating the latter in opposite directions. The terms fixed and movable dies employed herein and in the claims are used to describe the relative relationship between the dies irrespective of the fact that they are both rotatable as is well understood in the art.

The movable die 39 is mounted to rotate on a die shaft 22 journaled in the bearing 23. The shaft 22 carries a gear 24 which meshes with an idler gear 25 on a stud shaft 26 and which in turn is driven from the main shaft 15 by a gear 27. The bearing 23 for the die shaft and the bearing 28 for the stud shaft are both part of the rocker arm which comprises the branches 29 and 30 to the one side, see Fig. 2, and an arm or branch 32 to the other side in line with the branch 30. The said arms or branches are part of the rocker arm sleeve 33 which is preferably journaled on trunnions (not shown) instead of being pivoted directly on the main shaft so as to relieve the latter from the operating pressure on the rocker arm as will hereinafter appear. The main shaft extends through the rocker arm sleeve 33.

In order to bring the movable die into operative relationship with the fixed die, the rocker arm is operated by a toggle mechanism thus insuring smooth threads of uniform depth. Referring more particularly to Fig. 4 the numeral 35 denotes a cam shaft carrying the rocker cam 36 upon which runs a cam roll 37 carried by the slotted cam rod 100 or member 38. The latter is pivoted at 54 to a two armed lever 40 pivoted intermediate its ends at 41 to the frame. The portion 42 of the lever 40 forms a toggle link pivoted at 44 to the other, adjustable, toggle link 43. 45 is a guiding rod which carries a spring 46 which tends to break the toggle and which keeps the cam roll 37 on the cam.

36. The rod 45 is pivoted to the toggle at 48. 49 is a stop on the toggle adapted to come to rest upon the pads 50 on the frame. The cam shaft 35 is driven from the main shaft 15 by gears 27, 51, 52 and 53. 55 is a clutch to couple the shaft 35 to the gear 53 as will be understood. The clutch is operated by a treadle 56. Fig. 4 illustrates the parts in position when the treadle is depressed and the cam roll 37 is on the high part of the cam 36, when it will be seen, that the toggle 42—43 is straightened out against the tension of the spring 46 and the movable die is brought into engagement or co-operation with the fixed chuck and the threading is done. The dies operate on the cap so long as the cam roll 37 is on the high part of the cam 36 and in order to lengthen said part of the cam an auxiliary cam 60 may be adjusted as shown. It will further be noted that the pressure on the rocker arm by means of the toggle is applied directly in the plane of said rocker arm 32—30 so as to eliminate torsional strains.
- 25 When the threading operation is completed, the cap is removed from the lower die by means of a knock out mechanism which comprises a knock out rod 61 mounted to slide axially within the bearings 16 and 30 17 and the die 191. The rod 61 is reciprocated by means of the pivoted lever 62 which carries a cam roll 63 operated by a cam 64. A spring 65 within the bearing 17 keeps the roll on the cam.
- 35 When a cap 66 of the type shown in Fig. 3 is operated on, that is a cap without a center portion, the knock out mechanism may comprise a sleeve 67 adapted to engage the flange 68 of the cap. The sleeve is operated by a fork 69 on a rod 70 connected to the knock out rod 61 by an arm 71. In this instance a spring 72 may be used to keep the cam roll 63 on the cam 64.
- 45 While the caps may be placed on the die 191 by hand the output of the machine is greatly increased and accidents eliminated by using an automatic feed as hereinafter described. To this end there is provided a feed chute 75 comprising a side 76, a bottom 50 77 and a back 78, see Figs. 4 to 7. The back is cut down as at 79 so as to facilitate bringing the feed chute as close to the die 191 as possible. The side 76 is preferably terminated as at 80 and an adjustable mouth piece 55 81 is employed to adjust the size of the feed opening 82. The caps 21 are piled into the chute from the upper end thereof with the opening of the cap toward the side 76, Fig. 6. The caps roll down the chute by gravity during the operation of the machine. In order to prevent the caps from jumping out of the chute a top bar 83 may be placed on top of the caps and fastened with screws 84 which move in the slots 85 in the back 78 so as to 60 adjust the height of the chute to suit the size

of the caps. The mouthpiece 81 may be adjusted by screws 86 in a slot 87 and is placed so as to just catch the edge of the lowest cap in the chute and prevent it from falling out.

The chute 75, see Figs. 4, 9 and 10, is mounted on the fixed bracket 92 which is secured to the frame. Specifically the chute is pivoted and swiveled upon said bracket by means of a swivel block 112 which is screwed into the chute bottom 77 as at 110. Through the swivel block passes a bolt 90 which is adjustably secured in the slot 91 of the bracket 92 by means of nuts 113, 113. 111 is a spacing collar between the swivel block and the bracket. The chute is operated by a lever 93 pivoted to a swivel block 120 by a pin 94. The swivel block 120 is journaled on the frame 10 by a stud 121. The connection between the chute and the lever is as follows: 95 is a bolt which may be adjusted in the slot 96 in the piece 125 secured to the chute and in the slot 97 in the lever by means of nuts 117, 117 operating against suitable washers as 115 and 116. 114 is a journal block in the slot 96 which permits of a rocking, oscillating and swinging motion of the chute with respect to the lever 93, while a similar play or free motion is permitted the lever 93 between the one washer 115 and the washer 116. The lever carries a cam roll 98 95 which runs on the placing cam 99 and also carries another cam roll 100 which runs on the positioning cam 101. The two cams may be in one piece or are secured together as shown and fixed to the shaft 35. A spring 100 103 keeps the roll 100 on the cam 101.

The operation is as follows:—The chute or magazine 75 is filled with caps 21 as shown and this work is kept up during the operation of the machine. As the top of the chute 105 extends away from the machine this work may be done without danger to the operator. When the treadle is depressed the entire machine starts working and the timing of the cams is such that by means of the positioning cam 101 the chute is moved in a vertical plane toward and away from the die 191 and simultaneously therewith, by means of the placing cam 99 the mouth of the chute is moved laterally to place the cap on the said 110 die. This double movement of the chute is curvilinear and is accomplished through the co-operation of the swivel pivots 90 and 95, the pivoted lever 93, the cam rolls 98 and 100, and the cams 99 and 101.

The parts are shown in the drawings at the moment when the dies are together threading the cap. The chute has been lowered from the fixed die by a downward swinging motion in a place at right angles 125 to the axis of the die, the chute then moving about the center of pivot 90 and withdrawing from the cap placed on the die and while the cap is being threaded, the chute after the said swinging downward movement then 130

moves sidewise away from the die, then upward in line with the die, then toward the chuck placing the next cap thereon and then down into the position shown. The downward move of the chute frees the cap therefrom and it remains on the die.

During this movement of the chute the caps slide down therein by gravity and the threading of the cap on the die is accomplished. The rocker arm moves back by breaking the toggle and the knock out pushes the finished cap from the die and it falls to the ground or into a suitable receptacle.

The slots in the chute bracket, the chute and the lever 93 provide sufficient adjustment for the operation of the chute and the adjustment of the cams 36 and 60 is sufficient to thread the cap properly.

Besides operating on caps such as are shown in Fig. 1, the machine will feed automatically caps such as are shown in Fig. 8, where it will be noted that it makes no difference how the flange of the caps happen to lie in the chute because the caps are not fed to the die laterally with respect to each other or sidewise from the chute, which would be impossible with the caps shown in Fig. 8 because the flange on the cap to be fed might not be in front of the succeeding cap flange. But inasmuch as the chute slides or is drawn downwardly away from the cap in the plane of the latter, most any type of cap may be fed automatically by means of the chute shown and described. It will be seen that when the chute is filled with caps as in Fig. 8, the first cap to be placed on the die 191 has its flange in front of the succeeding caps, consequently said first cap is placed on the die, after which the chute by its downward movement withdraws from said first cap which is thus left on the die.

On the second movement of the chute it places the second or middle cap in Fig. 8 on the die 191 when of course the flange of the third cap will be between the face of the die and the flange of the second cap, this, however, presents no difficulty, because only a small sector of said third cap flange is thus caught between the middle cap and the die, and the lowering movement of the chute will carry said third cap away from the die and leave the middle cap on the die, it being of course understood that the feed opening of the chute has been adjusted to permit the caps in Fig. 8 to pass sidewise out of the chute and onto the die.

It will further be understood that I do not intend to limit myself to the exact disclosure herein, but that changes may be made within the principle of the invention and the scope of the appended claims.

I claim:—

1. In a cap threading machine in combination a pair of coöperating dies, a pivoted

receptacle adapted to receive a plurality of caps to be threaded, means for operating said receptacle on its pivot to position a cap upon one of the said dies and means for operating the latter.

70

2. In a cap threading machine in combination a fixed die, a movable die adapted to coöperate therewith, a pivoted receptacle adapted to receive a plurality of caps to be threaded, means for operating the said receptacle on its pivot to position a cap upon the said fixed die and means for rotating the said dies.

75

3. In a cap threading machine in combination a pair of coöperating dies, a pivoted receptacle adapted to receive the caps to be threaded, said receptacle having a feed opening, means for supporting said receptacle in a position to permit said caps to travel toward said feed opening by gravity, means for operating said receptacle on its pivot to automatically position a cap from the said feed opening and upon one of the said dies and means for operating the latter.

80

4. In a cap threading machine in combination a pair of coöperating dies, a receptacle for receiving the caps to be threaded, said receptacle having a feed opening, means for supporting said receptacle in a position to permit said caps to travel therein toward said feed opening, automatic means for operating said receptacle to position a cap from said feed opening and upon one of the said dies, automatic means for removing the threaded cap from the said one die and means for rotating the dies.

90

5. In a cap threading machine in combination a fixed die, a movable die, a receptacle adapted to receive the caps to be threaded, said receptacle having a feed opening, means permitting the caps in said receptacle to travel toward said feed opening by gravity, means for operating said receptacle to automatically place a cap from said feed opening and upon the said fixed die and means for rotating the dies.

105

6. In a cap threading machine in combination a pair of coöperating dies, a pivoted receptacle for receiving a plurality of caps to be threaded, means for adjusting the said receptacle to receive a given size cap, means for operating the said receptacle on its pivot to position a cap upon one of the dies and means for operating the latter.

110

7. The combination of a pair of dies, means for operating the same to thread caps, a receptacle for containing a plurality of caps to be threaded, a lever pivoted to the said receptacle and cams for operating said lever to actuate the said receptacle to automatically position the caps upon one of the said dies.

120

8. In a cap threading machine in combination a pair of coöperating dies, means adapted to receive a plurality of caps to be thread-

125

130

ed, said means having a cap outlet and mechanism for operating said cap receiving means to impart a curvilinear movement to the outlet thereof whereby to position a cap 5 upon one of the said dies.

9. In a cap threading machine in combination a pair of coöperating dies, a receptacle adapted to receive a plurality of caps to be threaded, said receptacle having a cap outlet 10 and mechanism for operating said receptacle whereby to impart a curvilinear movement to the outlet thereof to position a cap upon one of the said dies.

10. In a cap threading machine in combination a pair of coöperating dies, a receptacle adapted to receive a plurality of caps and provided with a cap outlet and means for operating said receptacle to place a cap upon one of said dies, said means operating 20 by a curvilinear movement toward and away from the said die.

11. In a cap threading machine in combination a die, means for supporting a cap to be threaded upon said die, means for operating 25 said supporting means to place the cap upon said die and to withdraw from said die by a movement in a plane perpendicular to the axis of the die after the cap has been placed upon the same.

30 12. In a cap threading machine in combination a die, a receptacle for receiving the caps to be threaded, said receptacle having a cap outlet and mechanism for imparting a curvilinear movement to said receptacle 35 whereby to cause the same to place a cap upon said die and to remove the cap from the receptacle by the latter withdrawing from the cap and die.

13. In a cap threading machine in combination a die, a receptacle for receiving the caps to be threaded, and means for operating 40 said receptacle into a position coaxial with the said die to place a cap thereon and for separating the cap from the receptacle by 45 withdrawing the latter in a direction at an angle to the axis of the said die.

14. In a cap threading machine in combination a pair of coöperating dies, a receptacle adapted to receive a plurality of caps and having a cap outlet, means for supporting 50 said receptacle in a position to permit the caps to travel toward said cap outlet by gravity, means for operating said receptacle to position said cap outlet in axial alinement with one of the said dies and with the lowermost cap upon the same, said means also serving to operate said receptacle away from said die in a direction other than that required for positioning the said outlet as aforesaid. 55

15. In a cap threading machine in combination a pair of dies a receptacle adapted to receive the caps to be threaded, supporting means, means for pivotally connecting said receptacle and said supporting means, a lever 60 pivotally connected to said receptacle and means for actuating said lever to impart a curvilinear motion to said receptacle to cause the same to place a cap directly upon one of the said dies. 70

16. The combination with a threading die, of means for placing a cap to be threaded on said die, said means comprising a receptacle for supporting a cap and mechanism for operating said receptacle in a direction 75 to place the cap upon the said die and for operating said receptacle in a direction at an angle to the first named direction away from said die.

17. In a cap threading machine the combination of a pair of coöperating dies, a receptacle adapted to receive the caps to be threaded and mechanism for operating said receptacle to place a cap upon one of said dies and for moving said receptacle away 85 from the die after the cap has been placed thereon, said last named movement being in a direction parallel with the plane of the top of the cap. 80

Signed this 24th day of November A. D. 90
1919.

HERMAN OSSWALD.
